MAGAZINE RACK

Carlton J. Gleed, Jr., San Francisco, Calif.

Application July 25, 1952, Serial No. 20,754

Term of patent 3½ years

(Cl. D33—2)

To all whom it may concern:

Be it known that I, Carlton J. Gleed, Jr., a citizen of the United States of America, resident of the city and county of San Francisco, State of California, have invented a new, original, and ornamental Design for a Magazine Rack, of which the following is a specification, reference being had to the accompanying drawings, forming a part thereof.

Fig. 1 is a perspective view of a magazine rack, showing my new design; and

Fig. 2 is an end elevational view thereof.

I claim:

The ornamental design for a magazine rack, substantially as shown,

CARLTON J. GLEED, JR.
